(57) **CLAIM**

The ornamental design for a barbecue light rack, as shown and described.

DESCRIPTION

FIG. 1 is a top front perspective view of a barbecue light rack showing my new design;

FIG. 2 is a bottom rear perspective view thereof;

FIG. 3 is a top front perspective view of the barbecue light rack in an extended position;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

The broken line showing of a grill in FIG. 3 is included for the purpose of illustrating environmental structure and forms no part of the claimed design.
